UNITED STATES PATENT OFFICE.

THOMAS ROLAND WOLLASTON, OF MANCHESTER, ENGLAND.

GAS-PRODUCER.

1,303,527.

Specification of Letters Patent. Patented May 13, 1919.

Application filed January 19, 1918. Serial No. 212,651.

To all whom it may concern:

Be it known that I, THOMAS ROLAND WOLLASTON, a subject of the King of Great Britain, residing at 26 Corporation street, Manchester, England, have invented certain new and useful improvements in Gas-Producers, of which the following is a specification.

This invention relates to improvements in gas producers having mechanically operated grates capable of crushing clinker and of discharging clinker and ash at regular and regulative rates, and has for its object to effect more perfectly than heretofore the control and disposal of clinker and ash 10 discharge from the gas producer.

In carrying out my invention, and with reference to the accompanying drawings, Figure 1 is a sectional elevation of a single-chambered gas producer provided with an ordinary fixed grate of inverted type, and arrangement of crusher rolls in relation thereto according to one form of my invention.

Fig. 2 is a sectional view at right angles 25 with Fig. 1, and in which other parts having reference to my invention are included. Fig. 3 is a horizontal cross section through line x , x , of Fig. 2.

Fig. 4 shows in outline and in elevation a 30 battery of producers, with the application of a number of water channels thereto.

Fig. 5 is a plan view of Fig. 4, with a detail added. Fig. 6 is a single producer in outline with the water trough indicated at 35 the part shown in section. Fig. 7 is a detail, on another scale, having more particular reference to Fig. 3.

a is a form of producer, of circular shape, about a diameter of which is a fixed grate b 40 of the inverted V type.

A cover or member c is shown at right angles with the axis of the grate, which, with the latter, divides the area of the base of the producer into four quadrants or sectors, 45 or approximately so. For each of these so called quadrants there is shown to be a pair of crusher rolls mounted below the level of the bottom edge of the grate b , and situated in parallel formation. The rolls of one quadrant are, however, disconnected from the rolls of another quadrant; thus, the pair of rolls shown at d are independent of the pair of rolls shown at e , as well as of the pairs of rolls shown at h and k . In Fig. 1, the 50 shafts upon which the rolls d and e are mounted will clearly be seen to be disconnected at the center line of the producer in the plane illustrated. These shafts are here provided with worm wheels l in gear with worms m , (see Fig. 7) similar worms and 60 wheels being used for all the rolls. Thus one pair of rollers may be rotating when another pair is at rest. In Fig. 7, a pair of worms m are shown attached to a common shaft 1, in gear connection with a shaft 4 65 by means of gear wheels 2 and 3, shaft 4 being driven from a suitable source of power.

The divisional member c is here formed as a cover to protect the end bearings of the rolls at that part, and also to bridge over 70 the gap between adjacent ends of said rolls.

Each pair of rolls is arranged so that the two rotate when in motion toward each other, in order to draw in the clinker to be crushed, as is well understood, and it is desirable that these rolls be of substantial 75 diameter such as indicated by the proportion illustrated, so as to insure the material being drawn between the same in a satisfactory manner. But each pair of rolls is capable 80 of independent motion, according to the source of power in connection therewith, so that one or more pairs may be in motion when others are not; or, the motion of one pair may be of a different or regulative rate 85 compared with that of another pair.

Each producer shown is provided with a water trough u , in the shape of two parallel channels of V form, the apex thus produced between them in each case being centrally situated, such as indicated in Figs. 2 and 4. The water lutes of the channels may have a level slightly below the level of the axes of the rolls d , e , h , and k , as indicated by broken line in Fig. 1, and the channels 95 themselves are preferably inclined, (see Fig. 6), toward a main conduit such as in Figs. 5 and 6. Any suitable form of conveyer such as a traveling bucket system as at position o in Fig. 4 may be adopted for the removal of the ash and broken clinker. To insure the same being effectually propelled into the main conduit, or out of the channels u , I provide hydraulic means such as pipes v (Fig. 2) capable of operating at their 100 orifices in the water lutes as jets when supplied with water at suitable pressure. Similarly the material may be propelled along the main conduit for removal at one extremity.

By the means described, it will be seen 110 that, the rolls when immersed to a large extent in the water lutes, or continuously in

contact therewith during complete rotation, are kept comparatively cool during working; the independent control of the movement of pairs of rolls makes them selective area for 5 area in which they are situated or enables the condition of the combustion zone of the producer to be largely regulated; and the application of hydraulic jets for removing accumulated ash and crushed clinker, enables the crusher rolls to be free for operation, besides insuring a rapid and satisfactory method of removal above named.

With water bottomed producers in which is employed low grade high ash coal it is 15 impossible to remove the ash and clinker by hand, and hydraulic means as described enable this to be accomplished effectively provided the material to be removed is comparatively small. The crusher rolls for breaking

up the same previously are thus essential, 20 and which result is better attained in the main by the use of the pairs of rolls in different sections of the grate area operating as described.

I claim:—

In combination, a water-bottomed gas producer, a grate area divided by members into distinct areas or sectors, a pair of crusher rolls in each area aforesaid, one pair of said crusher rolls capable of movement when 30 other pairs are at rest, a water lute below said rolls and in continuous contact with them, and water pipes leading from said lutes for hydraulic removal of the ash and clinker, substantially as herein set forth. 35

In testimony whereof I have affixed my signature.

THOMAS ROLAND WOLLASTON.
